UNITED STATES PATENT OFFICE.

FRED HIMMEL AND ISIDORE HIMMEL, OF NEW HAVEN, CONNECTICUT.

STORE-FRONT CONSTRUCTION.

Application filed May 12, 1925. Serial No. 29,736.

To all whom it may concern:

Be it known that we, FRED HIMMEL and ISIDORE HIMMEL, citizens, respectively, of the United States and Austria, residing at New Haven, in the county of New Haven and State of Connecticut, have invented a new and useful Improvement in Store-Front Construction; and we do hereby declare the following, when taken in connection with the accompanying drawings and the characters of reference marked thereon, to be a full, clear, and exact description of the same, and which said drawings constitute part of this application and represent, in—

Fig. 1 an inside view of the store-front construction embodying our invention.

Fig. 2 a sectional view on the line 2—2 of Fig. 1.

Fig. 3 a broken, vertical section, showing one of the bolts in position.

Fig. 4 a perspective view of one of the bolts detached.

Fig. 5 a perspective view of a section of the outer plate.

Fig. 6 a transverse, sectional view illustrating our invention as applied to division strips.

Fig. 7 a sectional view, illustrating a modified form of the outer strip.

Fig. 8 a section of the modified form of outer strip detached.

This invention relates to improvement in store-front construction, and particularly to store-front construction which includes a front strip and a back strip. These strips are usually connected together by bolts, the head of which is held in the outer strip and, extending through the inner strip, receives a nut by which the two strips are drawn toward each other, so as to grip the edges of sheets of glass between them. Difficulty is experienced in holding the screws in position, and the object of this invention is to provide means for supporting the screws, and the invention consists in the construction as hereinafter described and particularly recited in the claims.

In carrying out our invention, as shown in Fig. 2 of the drawings, for corners we

employ an outer strip 10 with flanges 11 and 12 arranged at the desired angle to set over the edges of sheets of glass 13 and 14. The central portion of the outer strip is provided at intervals with inwardly-extending sockets 15 formed by striking the metal inward, and preferably these sockets will be substantially square to receive the squared ends 16, turned at right angles from the threaded stems of bolts 17, which stems will project inward at right angles to the central portion of the outer strips. Preferably, the socket 15 will be formed with indentations 18 to enter notches 19 formed in the squared ends 16 of the bolts 17. These bolts extend through inner strips 20 of the desired form, having flanges 21 and 22 to engage with the inner faces of the sheets of glass 13 and 14, and a nut 23 is applied to the projecting end of the bolt 17, so as to crowd the two plates together. In this construction, it will be desirable to cover the outer strip with a facing 24 of sheet copper, and in this case, the inner strip may be formed from steel or other suitable metal.

In Fig. 6, we have illustrated the invention as applied to division strips, where they are used between two sheets of glass arranged in the same plane, the parts corresponding to the parts above described, and as clearly shown in Fig. 2 of the drawings.

Instead of forming the outer strip from steel, it may be formed from copper, in which case the center of the strip will be formed with inset bends 25, and in the inner wall 26 of this inset sockets 27 will be struck out to receive the ends 16 of bolts 17 as above described. The edges formed by the inset bend will be brought together so as to form a triangular inward projection, but the edges will be so close together that it will not mar the appearance of the structure, and avoids the necessity of a facing strip. In either case, we provide a firm mounting for the bolts, which bolts are readily entered into the sockets.

We claim:

1. A store-front construction, comprising an outer strip formed with inwardly-extend-

ing spaced sockets, and bolts having ends formed with indentations, and the ends of the bolts formed with notches to engage 10 therewith.

2. A store-front construction, comprising
5 an outer strip provided with inwardly-extending angular sockets, and bolts having angular ends turned at right angles and entered into said sockets, the said sockets

In testimony whereof, we have signed this specification.

FRED HIMMEL.
ISIDORE HIMMEL.
